C. Kornweiss

UNITED STATES PATENT OFFICE.

WILLIAM F. SCHWIESOW, OF RIPCOW, WISCONSIN.

GASOLINE TANK.

Application filed June 17, 1922. Serial No. 563,923.

To all whom it may concern:

Be it known that I, WILLIAM F. SCHWIESOW, a citizen of the United States, and resident of Ripon, in the county of Fond du

5 Lac and State of Wisconsin, have invented certain new and useful Improvements in Gasoline Tanks; and I do hereby declare that the following is a full, clear, and exact description thereof.

10 My invention refers to valves for liquid fuel tanks, such as described in my Patent No. 994,793, issued June 13, 1911, wherein a single tank is arranged, by a valve mechanism, to be tapped from a high level constituting a main fuel supply; and when the main fuel supply is exhausted, the valve can be operated to release an auxiliary supply of fuel, which auxiliary supply is, under ordinary conditions, sufficient in volume to supply 15 fuel to the engine of a motor-driven vehicle, whereby such vehicle can be driven to a convenient filling station for a renewal of the supply.

A primary object of my present invention 20 is to provide a compound valve unit, whereby the main fuel supply is controlled by a main valve unit to deliver fuel to the engine or to cut it off therefrom, and in conjunction with this main supply valve mechanism, an auxiliary valve mechanism associated therewith can be manipulated to open communication to the auxiliary supply after the main supply is exhausted.

Another object of my invention is to provide 25 means for locking the units of the compound valve, whereby the fuel supply from either source is sealed to thus prevent unauthorized parties from starting the engine, whereby thefts occur.

Another object of my invention is to provide 30 the compound valve mechanism as a unit, which can be assembled or removed in a simple manner, the construction and arrangement of the parts being such that the device, as a whole, can be manufactured at a minimum cost, said device being, also, so arranged as to eliminate wear and insure accurate seating of the valve units.

Another object of my invention is to provide 35 an arrangement and construction of the compound valve, whereby said valve will serve as a closure for the normal filling opening of the tank, the filling opening being aligned with a bottom receiving cup

for guidance and connection with said valve unit.

With the above and other objects in view, the invention consists in certain peculiarities in the construction and combination of parts, as will be hereinafter set forth with reference to the accompanying illustrations and subsequently claimed.

The drawing illustrates a fragmentary view of a fuel tank having associated therewith a compound valve embodying the features of my invention, with parts broken away and in section to more clearly show details of construction.

Referring by characters to the drawing, A—A' represent the top and bottom walls 79 of the tank. The bottom wall is apertured and has riveted or otherwise secured about the aperture a receiving cup 1, the bottom of which cup constitutes a sediment chamber that is drained by a pet-cock, and the side wall of the cup has fitted thereto a fuel feed pipe 2, which forms a communication from the tank to the carburetor of the engine. This pipe is provided with the usual check valve, as shown.

The mouth of the cup is internally threaded for the reception of the threaded end 3 of a hollow auxiliary valve stem 4. The end 3 of the auxiliary valve stem is contracted to form a discharge orifice 3', which orifice 35 is encased within the receiving cup. The auxiliary stem, just above its threaded end, is formed with a slight shoulder 4' for nested engagement with a gasket 5, which gasket, when the auxiliary stem is adjusted 40 downwardly, forms an air-tight seal between the tank and mouth of the cup 1. The upper end of the auxiliary stem is slidably fitted within the bore of a flanged collar 6, which flanged collar forms the filling mouth 65 of the tank. Hence the auxiliary stem projects through the tank body and its upper exposed end has formed therewith a hand-wheel 7, which hand-wheel is provided with a lock receiving aperture 7'. The wheel end 7 of the auxiliary stem is provided with a threaded opening 7" for the reception of the threaded end 8' of a main valve stem 8.

The main valve stem 8, at its lower end, is tapered for adjustment and seat with 105 relation to the cup discharge orifice 3'. The upper end of the main valve stem, which projects above the auxiliary valve stem, is

formed with a wheel or knob 9, which wheel is, also, apertured for receiving the hasp 10 of a lock 10', the lock being of any desired type.

5 In this exemplification of my invention, the lock hasp 10 is shown having a lug 10" extending therefrom for engagement with a spur 11 which projects from the flange collar 6. The hollow auxiliary stem is provided with a main port 12 normally positioned a predetermined distance above the bottom wall of the tank, whereby the contents of the tank can be drained down to this point, and below this point, the body 15 of the liquid may be termed the "auxiliary supply."

The lower end 3 of the hollow valve stem is also provided with an auxiliary port 12', which port, when the valve stem is seated 20 in its normal position with relation to the mouth of the cup 1, is below the bottom of the tank and hence communication between the auxiliary valve port and tank, under normal conditions, is cut off.

25 The auxiliary valve stem, as shown in the drawing, is in its normal position and the main valve stem is also in its normal closed position with relation to the discharge orifice 3'. In this position, the compound 30 valve, constituting the main and auxiliary stems, have their hand-wheels in close proximity, and the locking orifices of the two wheels are alined, whereby the hasp of lock 10' can engage both wheels to lock them 35 against rotation. When the hasp is in its locked position with relation to the hand-wheels of the valve units, its locking lug 10", as shown in the drawing, extends below the plane of the collar spur 11. Hence, 40 when the parts are in this position, there is no feed of liquid from the tank to the carburetor, and furthermore no feed can be obtained until the locked parts are disengaged. Owing to the fact that the locking 45 lug and spur 11 are intermeshed, the valve unit, as a whole, cannot be removed from its seat, due to the fact that its locking lug and spur will prevent rotation of the auxiliary valve member with relation to its 50 threaded union in the receiving cup 1. Hence, all of the parts are locked and the device will insure the owner of the motor-driven vehicle against theft, due to the fact that without the proper key, no fuel can be 55 fed to the engine.

While I have shown some means to prevent rotation of the auxiliary hollow stem in its seat, obviously this means can be varied indefinitely within the scope and 60 knowledge of a skilled mechanic, and furthermore various other modifications of the structure shown may be made without departing from the spirit of the invention. As for example, the lower threaded end of the 65 hollow spindle 3 may form a smooth bore

connection with the mouth of the receiving cup, in which case the upper end of the hollow stem could be exteriorly threaded for a corresponding threaded union with the bore of the flanged collar. The results would be 70 the same as the threads would only be reversed from the top to the bottom of the structure.

It is, also, obvious that when it is desired 75 to fill the tank, the compound valve mechanism can be readily removed as a whole and that said valve mechanism is adjusted to the filling mechanism, serving the purpose of a filling opening plug, which can not be tampered with, due to the fact that the 80 parts are locked and hence cannot be rotated to effect disengagement.

While I have shown and described a simple exemplification of my invention minutely 85 with respect to all of its details, it is understood that I may vary the mechanical features of the invention, as described, within the scope of the claims as they may be hereafter interpreted by those skilled in the art.

90 Particular attention is called to the fact, that owing to the construction of the valve stem 8 in an emergency, such as in case of leakage of the carburetor, the supply of fuel can be quickly and readily cut off by 95 manipulating the valve stem hand wheel 9, which hand wheel is accessible at the top of the tank and the operator is thereby relieved of the annoyance of crowding under a car in order to cut off the supply of fuel; 100 this being the general practice.

I claim:

1. In a tank having a fuel receiving cup in communication with the bottom, and a filling opening in its top wall alined therewith; the combination of a compound valve mechanism comprising an auxiliary hollow valve stem for engagement with the filling opening and cup, the same being provided with a bottom discharge orifice and main 105 and auxiliary ports at different elevations with relation to the bottom wall of the tank, means for adjusting the auxiliary stem relative to the receiving cup, whereby the auxiliary port is open or closed with relation 110 to the fuel supply, a main valve extending through the hollow stem for controlling the discharge orifice of the auxiliary stem, and key controlled means for locking the main and auxiliary stems against rotation. 115

2. In a tank having a filling mouth in its upper wall and an alined discharge cup in communication with the bottom wall of the tank, the cup being provided with a threaded mouth, a hollow main stem having its 125 lower end in threaded union with the cup mouth and terminating with a discharge orifice, the hollow stem being provided with a lower auxiliary port and an upper main port, the lower port being normally closed 130

with relation to the body of the tank, a main valve stem extending through the hollow valve stem and in threaded union therewith, the main valve stem and auxiliary valve stem being extended above the tank body and provided with independent actuating wheels or handles, and key controlled means for locking the wheels or handles together and for preventing bodily rotation of the auxiliary stem, when the valve members are closed against flow of the fluid.

In testimony that I claim the foregoing I have hereunto set my hand at Ripon, in the county of Fond du Lac and State of Wisconsin.

WILLIAM F. SCHWIESOW.
